UNITED STATES PATENT OFFICE.

SUMNER WILTSE, OF DETROIT, MICHIGAN, ASSIGNOR TO WILTSE APPLIANCE COMPANY, A CORPORATION OF MICHIGAN.

FUEL-SUPPLY SYSTEM FOR INTERNAL-COMBUSTION ENGINES.

Application filed April 1, 1927. Serial No. 180,176.

One of the objects of my invention is to provide means for controlling the flow of excess fuel from the fuel pumping means to the carburetor of an internal combustion engine.

Another object of my invention is to provide means for controlling the flow of fuel from the pump to the carburetor which will eliminate the necessity of an external bypass line or return line for taking care of excess fuel.

With the above and other objects in view, my invention consists in the arrangement, combination and construction of the various parts of my improved device, as described in the specification, claimed in my claims and shown in the accompanying drawings, in which:

Fig. 1 is a central sectional view of my improved device.

Fig. 2 is a view taken on line 2—2 of Fig. 1. Fig. 3 is a side elevation, with parts broken away, showing a modification of my device.

Fig. 4 is a view taken on line 4—4 of Fig. 3.

I have shown a fuel pump comprising a casing 10, the interior of which is divided into two compartments 11 and 12 by a partition 13 in which are journaled shafts 14 and 15. On the ends of shafts 14 and 15 in compartment 11 are secured rotor blades 16 and 17 of the shape shown in Fig. 2 which are so arranged as to pump fuel into and out of compartment 11 when they are rotated, but are provided with a slight clearance from each other and from the sides of the compartment so as to avoid wear from gritty particles which may be in the fuel pump. On the shafts 14 and 15 in compartment 12 are mounted gears 18 and 19 which are positioned to mesh. An extension 20 is provided on shaft 14 and is designed to be engaged by the end of camshaft of an internal combustion engine or any other suitable driving means. The compartment 12 is provided with an apertured cover 21 through which shaft 14 extends. Compart-

ment 11 is provided with a cover 22. Covers 21 and 22 are secured to casing 10 by means of bolts 23 inserted through suitable apertures in the covers and through the holes 24 in the casing 10. The joints between the covers and casing may be sealed by interposing a lead gasket therebetween. The cover 22 is cup-shaped and the rim 25 thereof bears against the outer edge of the casing 10 leaving the inner edge of the casing 10 free to support a diaphragm 26 which is positioned thereon.

In the central portion of cup 22 is provided a threaded aperture 27 in which is fitted an internally and externally threaded sleeve 28. A coil spring 29 is positioned in the sleeve 28 with one end bearing against the central portion of the diaphragm 26. Screw plug 30 is inserted in the outer end of sleeve 28 and bears against the outer end of coil spring 29, thus adjustably holding it in position against the diaphragm 26. Cap 31 is screwed upon the outer end of sleeve 28 and a gasket 32 may be inserted between the cap 31 and the end of sleeve 28 to effectively seal the same.

Chamber 11 is provided with a fuel inlet passage 40 in which is fitted a fuel feed pipe 41 which leads to the fuel supply. The opposite side of chamber 11 is provided with a fuel outlet passage 42 which is fitted with a fuel outlet pipe 43 which leads to the carburetor of an internal combustion engine (not shown).

Chamber 12 is provided with an oil inlet passage 50 in which is fitted an oil inlet pipe 51 which leads to the oil pump of an internal combustion engine (not shown). The entire pump mechanism is preferably attached to the forward or rear end of the crankcase of an engine in a position so that the end of the camshaft may engage the extension 20 of shaft 14 and thereby drive the pump. It is to be understood, however, that it may be otherwise driven as, for instance, by the distributor shaft.

In Figs. 3 and 4 I have shown a modification in which the aperture 27 and sleeve 28 are eliminated and a flat spring 40 is substituted by the coil spring 29. The central body portion of the flat spring 60 bears against the central portion of the diaphragm while its ends 61 and 62 bear against the inside of the cover 22. Both coil spring 29 and flat spring 60 are normally tensioned to hold the diaphragm 26 firmly against the edge of the casing 10, thereby sealing the compartment 11.

In operation, the rotation of the shaft 14 causes a rotation of the rotor 16, and the gear 18 which meshes with gear 19 rotates shaft 15 and rotor 17. The rotors draw fuel from the tank (not shown) through the pipe 41 and opening 40 and force it out through opening 42 and pipe 43 to the carburetor (not shown). In order to avoid flooding the carburetor, a restriction valve which may comprise merely a filler for pipe 43 with a restricted longitudinal opening therein, or any

other suitable construction, is positioned within pipe 43 adjacent the opening 42. The restricted opening is of a size which will insure adequate but not excessive supply of fuel to the carburetor and will build up a back pressure in the pump chamber. When a larger quantity of fuel is presented to the restricted opening in pipe 43 than will readily pass therethrough the same will back up 10 on the outlet side of the pump, build up a pressure there sufficient to force the diaphragm 26 outwardly against the tension of spring 29 or spring 60, and permit the excess fuel to pass back to the inlet side of the pump 15 which will prevent the intake of more fuel through inlet opening 60 until the outlet pipe 43 with its restricted opening is able to carry away the excess within the pump. The necessity of an outside bypass or a return line is 20 thus eliminated.

It will be quite apparent that the amount of fuel pumped by the pump elements and correspondingly the pressure in the pump chamber will vary in relation to the speed of 25 rotation of the elements and that the amount of opening of the diaphragm 26 will vary proportionately to permit of greater slippage at higher speeds.

It will be obvious that various changes 30 may be made in the arrangement, combination and construction of the various parts of my improved device without departing from the spirit of my invention, and it is my intention to cover by my claims such changes as 35 may be reasonably included within the scope thereof.

What I claim is:

1. In combination, a pump housing having 40 fluid inlet and outlet passages, a pump element in the housing, a movable diaphragm forming one wall of the housing, an extension of the housing positioned beyond the diaphragm, an adjustable member in the extension and yielding means positioned 45 between the diaphragm and adjustable means, whereby adjustable pressure may be exerted

on the diaphragm from without the housing proper.

2. In combination, a pump housing having fluid inlet and outlet passages, a pump element in the housing, a movable diaphragm forming one wall of the housing, an extension of the housing positioned beyond the diaphragm, an adjustable plug threaded in the extension, and yielding means positioned 55 between the diaphragm and plug, whereby adjustable pressure may be exerted on the diaphragm from without the housing proper.

3. In combination, a pump housing having fluid inlet and outlet passages, a pump element in the housing, a movable diaphragm forming one wall of the housing, a sleeve forming a part of the extension and open to the diaphragm, an adjustable plug closing the other end of the sleeve and yielding means 60 positioned between said diaphragm and plug, whereby adjustable pressure may be exerted 65 on the diaphragm from without the housing proper.

4. In combination, a pump housing having fluid inlet and outlet passages, a pump element in the housing, a movable diaphragm forming one wall of the housing, a sleeve forming a part of the extension and open to the diaphragm, means closing the other end 70 of the sleeve and yielding means positioned between said closure and diaphragm for exerting pressure on the diaphragm from without the housing proper.

5. In combination, a pump housing having fluid inlet and outlet passages, a pump element in the housing, a movable diaphragm forming one wall of the housing, a cap over 75 the diaphragm, a sleeve on said cap, a plug threadably received by the interior of said sleeve, a cap sealing the outer end of said sleeve, and yieldable means interposed between said plug and said diaphragm, said plug being adjustable whereby to vary the 80 tension of said yieldable means.

SUMNER WILTSE.
